UNITED STATES PATENT OFFICE.

EDWIN F. HULBERT, OF MILWAUKEE, WISCONSIN, ASSIGNOR TO NATIONAL PAPER CAN COMPANY, OF MILWAUKEE, WISCONSIN, A CORPORATION OF DELAWARE.

MACHINE FOR FORMING SHELLS OF PAPER OR THE LIKE.

1,380,104.

Specification of Letters Patent.

Patented May 31, 1921.

Application filed December 27, 1917, Serial No. 209,185. Renewed October 25, 1920. Serial No. 419,484.

To all whom it may concern:

Be it known that I, EDWIN F. HULBERT, a citizen of the United States, residing at Milwaukee, in the county of Milwaukee and State of Wisconsin, have invented a new and useful Improvement in Machines for Forming Shells of Paper or the like, of which the following is a full, clear, and exact description of same, reference being had

10 to the accompanying drawings, forming part of this specification, in which—

Figure 1 is a vertical section through the machine.

Fig. 2 is an elevation of the head of the 15 machine, partly in section, showing the spray heads.

Fig. 3 is a section on the line III—III of Fig. 2.

Fig. 4 is a vertical section through the 20 wax pump and driving connections.

Fig. 5 is front elevation of the wax valve housing.

Fig. 6 is a vertical section along the line 25 VI—VI of Fig. 5.

Fig. 7 is a vertical section through the pressure operated thermostat, and

Fig. 8 is a plan view of the thermostat with the cover plate removed.

The present invention relates to machines 30 for forming shells of paper or the like, and more particularly to the mechanism in such machines for supplying a heated impregnating or waterproofing material, such as paraffin wax, to the paper.

One object of the invention is to provide 35 means for controlling the heating of the wax. Another object is to provide a machine in which the shell forming mechanism is heated by the wax supplied from

40 the reservoir. Another object is to provide means for lubricating certain moving parts by the heated wax. Other features of the invention relate to certain arrangements and combinations of parts hereinafter more particularly pointed out, the advantages of

45 which will be apparent to those skilled in the art, from the following description.

The machine has a standard 2 in which 50 is located a reservoir 3 for the wax, preferably paraffin. Carried at the top of the standard is a head or housing 4 which encloses the mechanism for winding the paper strips into shells. This mechanism includes a mandrel 5 upon which the shell is wound.

55 The paper is fed to the mandrel by feed

rolls 6. An endless chain belt 7 surrounds the mandrel and cooperates therewith to press the layers of paper into the completed shell. After the shell is wound on the mandrel it is stripped therefrom by an ejector 8. During the shell winding operation, tension is applied to the endless chain 7 to cause it to hug the mandrel and compress the shell against it. This tension is continued after the strip is wound on the mandrel to further consolidate the walls. Then the chain is released and the ejector 8 is moved over the mandrel, stripping the shell therefrom. After a shell is ejected, the feed rolls 6 supply another strip of paper 70 to the mandrel and the cycle of operations is repeated. The details of the shell winding and paper feeding mechanisms do not form a part of the present invention but are covered in my co-pending applications 75 Serial No. 209,184, and Serial No. 209,186 filed of even date herewith.

As the paper is fed to the mandrel it is impregnated with hot paraffin supplied by upper and lower spray heads 10 and 11. The spray heads 10 and 11 are supplied with hot paraffin by means of a pump 12 located in the reservoir 3 through piping connections 13.

The pump 12 is a gear pump of the usual structure comprising the two gears 15 and 16. The gear 15 is carried on the lower end of the hollow drive shaft 17. The drive shaft 17 is inclosed in a tubular housing 18 hung from a bracket 19 supported at the top of the reservoir. The drive shaft 17 carries at its upper end a bevel gear 25 which meshes with another beveled gear 26 carried by the continuously driven shaft 27. The hot paraffin is carried up from the pump 90 through a pipe 30 inclosed in the hollow drive shaft 17. The pipe 30 communicates through a valve 31 with the supply pipe 13 of the spray heads 10 and 11. The valve 31 is provided with a tappet rod 32. The tappet rod is operated by a cam (not shown) in timed relation to the winding and ejecting mechanism to open the valve during the time the shell is being wound and consolidated on the mandrel 5, and to close 100 the valve 31 when the ejector is operating to strip the shell from the mandrel. The spring pressed by-pass valve 35 is provided for by-passing the paraffin when the valve 31 is closed. The by-pass valve 35 opens 110

55

into a pocket 36 in which is located the gear 25. The hot paraffin passing into the pocket 36 serves to lubricate the gears 25 and 26. The paraffin in the pocket 36 leaks down 5 through the clearance space around the drive shaft 17 thus lubricating it. The excess wax spills over the top of the pocket and drips back into the reservoir. An excess of wax is supplied to the paper from the spray- 10 heads 10 and 11. This excess wax serves two purposes. It bathes the chain and its carrying rolls, the ejector, and the various bearings in the winding head. As all these parts are maintained hot, the liquid paraffin 15 makes a good lubricant for the bearing surfaces. The other function of the hot paraffin is to maintain the winding head hot. The paraffin is discharged through the winding mechanism by the spray heads 10 20 and 11 and it is found to be sufficient so that no separate heating means need be employed. The excess paraffin drips through drain 40 in the bottom of the housing 4 and returns to the reservoir where it is re- 25 heated.

The housing 4 and the inclosed winding mechanism are located immediately above the hot paraffin reservoir 3 and are in communication with it through the drain opening 30 40. The heat rising from the reservoir also serves to maintain the winding mechanism at the proper degree of heat. It is found in operating the machine that after the paraffin in the reservoir 3 is brought up 35 to the proper temperature and the pump 12 operated for a short time to pump the hot wax to the winding mechanism, the winding mechanism is brought to the proper degree of heat. The winding mechanism is simplified in that no separate heating means need be supplied to it:

The mechanism for maintaining the wax in the reservoir 3 at the proper temperature is as follows:—The reservoir 3 is a thin 45 walled container and is surrounded by a jacket 50 containing a mixture of water and alcohol. Below the jacket 50 is an electrical heating element 51 supplied with current through the lead wires 52. The heating current 50 is regulated by a pressure operated thermostat 60 which controls a relay 61 in the heating circuit 52. The thermostat 60 is connected to the upper part of the jacket 50 by pipe 65. The thermostat comprises 55 a diaphragm chamber 70 in which is located a thin metal diaphragm 71. The diaphragm 71 is formed of a dished piece of resilient sheet metal like the bottom of an oil-can and is arranged to snap upwardly when the 60 pressure in the chamber 70 below it increases sufficiently. Resting against the top of the diaphragm 71 is a tappet rod 72, which extends into the contact box 75. Carried on the upper end of the rod 72 is a metal cup 65 76 insulated from it by the insulating washer

77. A spring 78 bears against the top of the cup 76 and tends to hold it in contact with two stationary contacts 80 and 81. The cup 76 bridges the contacts 80 and 81 and closes the circuit which operates the relay 61. The spring diaphragm 71 may be adjusted to snap upwardly at the proper pressure, by means of a ring 85. Rings 85 having different size openings in them may be employed, the smaller the opening in the ring 85, the greater the pressure necessary to operate the diaphragm 71.

The finer adjustment of the thermostat is made by varying the proportion of alcohol and water in the jacket 50. This proportion is chosen so that if the heat exceeds the desired temperature, a sufficient pressure will be exerted under the diaphragm 71 to raise it. The upward movement of the diaphragm 71 lifts the contact cup 76 away 35 from the stationary contacts 80 and 81, breaking the circuit, deenergizing the relay 61 and shutting off the current to the heater 50. If the temperature drops, the pressure is reduced and the diaphragm 71 allowed to snap back into its lower position. This causes contact cup 76 to bridge the stationary contacts 80 and 81, energizing the relay and switching the current into the heater 50. By means of this pressure controlled thermostat, the temperature of the paraffin in the reservoir 3 can be accurately maintained at the desired point.

The tappet rod 72 is of such a length that when the diaphragm 71 snaps to its lower position, the tappet rod is out of contact with the cup 76 and its insulating washer 77. The lost motion thus provided insures a quick break of the circuit, and insures a positive seating of the contact cup 76 when 105 the diaphragm is in its lower position.

While the preferred embodiment of the invention has been illustrated and described it is to be understood that the invention is not limited to its illustrated embodiment but 110 may be embodied in other structures within the scope of the following claims.

I claim:

1. A machine for making shells of paper or the like, comprising a mandrel and associated mechanism for winding a sheet of material into a shell, means for supplying a heated wax to the mandrel while the sheet is being wound, means for ejecting the wound shell from the mandrel, and means 120 for interrupting the flow of the wax during the ejecting operation; substantially as described.

2. A machine for making shells of paper or the like, comprising a mandrel and associated mechanism for winding a strip of material into a shell, and means for supplying heated wax to the winding mechanism comprising a continuously driven pump, a supply pipe, a valve in the supply 130

pipe, and means for opening and closing the valve to supply wax to the winding mechanism during a part only of its cycle of operations; substantially as described.

- 5 3. A machine for forming shells of paper or the like, comprising a mandrel and associated mechanism for winding a strip of material into a shell, a pump for supplying wax to the winding mechanism, connections 10 for driving the pump, and means for diverting a portion of the wax supplied by the pump for lubricating the said pump driving connections, substantially as described.

4. A machine for forming shells of paper

or the like, comprising a mandrel and associated mechanism for winding a strip of material into a shell, a reservoir for heated wax, a pump for supplying heated wax from the reservoir to the winding mechanism, and means for maintaining the reservoir at the proper temperature, including a jacket surrounding the reservoir and containing an evaporable liquid, and a thermostat operated by the pressure in the jacket; substantially as described.

In testimony whereof, I have hereunto set my hand.

EDWIN F. HULBERT.
